G. H. DRABENSTOTT,
SAWING AND BORING DEVICE,
APPLICATION FILED SEPT. 23, 1920.

1,377,961.

Patented May 10, 1921.

UNITED STATES PATENT OFFICE.

GLENN H. DRABENSTOTT, OF WOOSTER, OHIO.

SAWING AND BORING DEVICE.

1,377,961.

Specification of Letters Patent.

Patented May 10, 1921.

Application filed September 23, 1920. Serial No. 412,328.

To all whom it may concern:

Be it known that I, GLENN H. DRABENSTOTT, a citizen of the United States, residing at Wooster, in the county of Wayne and 5 State of Ohio, have invented a new and useful Sawing and Boring Device, of which the following is a specification.

My invention relates to devices for cutting openings in floors and partitions in 10 buildings, and its principal object is to provide simple and efficient means for making suitable openings in floors and partitions to admit electric wires therein for illuminating and other purposes; and it 15 consists in mounting an electric motor upon a slideable base in combination with a circular saw and supporting frame geared directly to said motor, and operable therewith; and it further consists in combining 20 with said motor means for boring through beams and joists in buildings for the admission of electric wires, independently of said sawing mechanism—all as hereinafter 25 fully set forth and stated in the appended claims.

My invention is illustrated by the accompanying drawings, in which similar letters and figures of reference indicate like parts.

Referring thereto, Figure 1 is a side view 30 of a motor sawing and boring device embodying my invention, showing the saw mechanism in elevated position. Fig. 2 is a similar side view showing the saw mechanism in operative position, and also the attachment for boring.

Fig. 3 is a view of the same inverted, showing the gear mechanism more distinctly. In the drawings, A is a motor, similar to such as are in common use, and requires no further description. It is pivotally mounted on a base B, having anti-friction rollers b b b b at its ends (best shown in Fig. 3); the pivoted connection is preferably made by means of a pivot rod 13 40 passed laterally through the sides of the base B, at a point near the bottom of one end of the motor, whereby the weight of the mechanism is nearly evenly divided endwise. A flange 14 at the bottom of the motor and 45 on each side thereof adjacent to the sides of the base affords means for pivotally securing the motor between the sides of said base so as to tilt endwise a limited distance freely. A circular saw C is mounted operatively be- 50 tween arms 10 10 rigidly secured to the body

of said motor, and is provided with a safety guard 1, preferably attached to the end of the base B. A suitable gear wheel 8, mounted between said arms, is driven by the motor pinion 7, and is adapted to be thrown out of and into gear by a hand lever 9 operable on a standard K secured to said frame, in the usual and well known way of changing gear by lateral shift of the wheel 8 on the shaft 12. The latter communicates motion to the saw by the bevel gear wheels 11, mounted at the ends of said arms 10, as best shown in Fig. 3. A thin metal disk D is mounted directly in the path of and at the rear of the saw C, and normally projects 60 downwardly a limited distance to follow said path, and aid the travel of the saw. It is operable a short distance vertically through a support 17, and reciprocates 65 therein by means of a vertical shaft and spiral spring S, suitable to the depth of the cut of the saw, which is regulated by means of a hand lever H pivotally mounted at the opposite end of the base, and provided with a slideable notched sleeve 5, adapted to 70 engage a stud 16 providing laterally from the rear. A pair of arms 15 15 extend rearwardly and upwardly from the rear end of the motor, and are united at their upper ends by a cross bar 3 which serves as a hand 75 hold to guide the direction of the saw, and tilt it upon the pivot rod 13, as aforesaid.

In addition to the saw mechanism, I provide convenient means for boring holes through joists and beams of buildings by 80 adapting the opposite end of the motor to actuate a flexible rotary shaft G, having at its outer end a chuck I to hold and actuate a suitable boring bit J, in the usual and well known way. Said flexible shaft is 85 detachably secured to the extended end of a shaft carrying a worm gear wheel E mounted between the upright arms F, and driven by the worm gear pinion 4, which is secured on the extended end of the motor shaft, 90 in the usual way of connecting worm gears. Said rotary flexible shaft may be readily detached, when not in use, and provision 95 may be made for throwing the operative mechanism therefor out of gear, if desired, 100 but this is not essential, and therefore not shown herein.

A suitable handle 2 may be secured on the top of the motor as a convenience for handling the device, and placing it in opera- 110

tive position, and to aid in guiding the direction of the saw.

A small motor, similar to those in common use, of about one half horse power, or 5 less, may be readily adapted to and mounted to actuate said saw and boring mechanisms independently of each other, as stated.

I do not limit my claims to mere matter of form, and changes of parts may be made 10 without departing from the scope of my invention; but having thus fully described my invention, what I claim as new and desire to secure by Letters Patent is—

1. In a device of the character described, 15 in combination, a slidable base, a motor mounted to swing endwise on said base, a circular saw attached to said motor, and driven by mechanism intermediate the same,

and a guiding disk mounted to travel in the path of said saw, substantially as set forth. 20

2. In a device of the character described, 25 in combination, a slidable base, a motor hinged thereon to swing endwise a limited distance, a circular saw mounted between arms secured to one end of the motor, a rotary flexible shaft having a boring tool at its outer end, and a worm gear at the other end of said motor arranged to drive said shaft, and means for driving said saw and said boring tool independently. 30

In witness whereof I hereunto set my hand this 29th day of July, 1920.

G. H. DRABENSTOTT.

In presence of two witnesses:

WALTER J. MOUGEY,
HIRAM B. SWARTZ.
